UNITED STATES PATENT OFFICE

161,574

ADJUSTABLE COUCH CHAIR

Simon Deutsch, Miami Beach, Fla.

Application May 25, 1950, Serial No. 10,163

Term of patent 14 years

(Cl. D15—1)

To all whom it may concern:

Be it known that I, Simon Deutsch, a citizen of the United States, residing at Miami Beach, in the county of Dade and State of Florida, have invented a new, original, and ornamental Design for an Adjustable Couch Chair, of which the following is a specification, reference being had to the accompanying drawings, forming a part hereof.

I claim:

The ornamental design for an adjustable couch chair, as shown.

SIMON DEUTSCH.
